Primary Examiner — Ian Simmons*Assistant Examiner* — Charles Hanson*(74) Attorney, Agent, or Firm* — Beyer Law Group LLP(57) **CLAIM**

I claim the ornamental design for a multipurpose reusable carrier bag, substantially as shown and described.

DESCRIPTION

FIG. 1 is a top perspective view of a multipurpose reusable carrier bag showing my new design.

FIG. 2 is a top perspective view thereof.

FIG. 3 is a top perspective view thereof in an upright position.

FIG. 4 is a top view thereof.

FIG. 5 is a bottom view thereof.

FIG. 6 is a right side view thereof.

FIG. 7 is a left side view thereof.

FIG. 8 is a front view thereof.

FIG. 9 is a rear view thereof; and,

FIG. 10 is a rear view thereof, showing a handle thereof folded back onto itself.

The broken lines in the Figures show portions of the reusable carrier bag which form no part of the claimed design.

The shade lines in the Figures show contours and not surface ornamentation.
